UNITED STATES PATENT OFFICE.

WILLIAM T. SHERMAN, OF TROY, NEW YORK, ASSIGNOR TO HENRY L. HUGHES CO., INC., OF NEW YORK, N. Y., A CORPORATION OF NEW YORK.

TUBE-PLATE-STRIPPING MACHINE.

1,370,610.

Specification of Letters Patent.

Patented Mar. 8, 1921.

Application filed June 3, 1920. Serial No. 386,191.

To all whom it may concern:

Be it known that I, WILLIAM T. SHERMAN, a citizen of the United States of America, residing at Troy, in the county of Rensselaer and State of New York, have invented new and useful Improvements in Tube-Plate-Stripping Machines, of which the following is a specification.

Reference may be had to the accompanying drawings, and the reference characters marked thereon, which form a part of this specification. Similar characters refer to similar parts in the several figures therein.

This invention relates to brush-making apparatus and particularly to apparatus for making rubber brush-pads in accordance with the method set forth in United States Letters Patent No. 1,324,178, dated December 9, 1919, granted upon an application filed by me, to which patent reference may be had for a more complete understanding of the nature and objects of the present invention.

In the manufacture of rubber brush-pads in accordance with said patented invention, a perforated rubber pad formed with numerous perforate openings is supported between two clamp-plates provided with perforations or openings corresponding in number and location with the openings in the rubber-pad, while tubes corresponding in number and arrangement with the openings in the pad and mounted upon a supporting tube-plate are forced through the respective openings in one of said clamp-plates and the rubber-pad into the respective openings in the other clamp-plate.

Bristles are then inserted within the respective tubes after which the tubes are withdrawn from the openings in the clamp-plates and pad, leaving the bristles within the respective openings in the pad. The openings in the pad are quite small and are temporarily enlarged by the insertion of the respective tubes. The pad being made of soft vulcanized rubber closely grips and frictionally holds the respective tubes so that it is quite difficult to withdraw the tubes from the rubber pad.

The principal object of the present invention is to provide means whereby the tube-plate can be withdrawn from the rubber-pad

and clamp-plates in the manufacture of a brush in accordance with said patented method.

Figure 1 of the drawings is a view in front elevation of a tube-plate-stripping machine embodying my invention.

Fig. 2 is a view in side elevation of the same.

Fig. 3 is a top plan view of the same. 60

Fig. 4 is a top plan view of the same partly broken away and shown in section.

Fig. 5 is a vertical cross-section of the same taken on the broken line 5—5 in Fig. 4.

Fig. 6 is a longitudinal vertical section 65 taken on the broken line 6—6 in Fig. 4.

Fig. 7 is a longitudinal section taken on the broken line 7—7 in Fig. 4.

Fig. 8 is a top plan view showing two tube-connected plates for operation upon 70 which the machine shown in the other figures of the drawings is adapted.

Fig. 9 is a vertical cross section taken on the broken line 9—9 in Fig. 2.

Fig. 10 is a vertical section taken on the 75 broken line 10—10 in Fig. 1.

Referring to the drawings wherein the invention is shown in preferred form, 21 is the bed of the machine, and 22 is an overhanging-arm, having a head, 23, upon which 80 a handle, 24, is pivotally mounted at 25.

Within the head, 23, is mounted a plunger, 26, movable toward and from the bed, 21, said plunger being connected by a link, 27, with the handle, 24, to form a toggle-joint 85 whereby the plunger, 26, is lowered and raised by the raising and lowering of the handle, 24.

At the front, rear and opposite sides of a space on the bed under the plunger, 26, I 90 mount upon the bed claw-members, 28—28—28, at the front, 29—29—29, at the rear and 30—30 on the respective sides of said space.

The claw-members, 29, may be mounted in fixed position upon the bed with their 95 claws, 31, overhanging said space.

The claw-members, 28, are pivotally mounted at 32, whereby they are adapted to be swung to and from a position in which their claws, 33, shall overhang said space, 100 and they may be swung to and from said position by hand or in any known manner.

The claw-members, 30, are pivotally mounted at 34, whereby they are adapted to swing to and from a position in which their claws, 35, shall overhang said space.

These claw-members, 30, are yieldingly held by coil-springs 36, in position for their claws, 35, to overhang said space, and they may be forced apart against the force of the springs 36, in any known manner so that 10 their claws shall not overhang said space.

As a means for forcing apart the claw-members, 30, I have shown a pair of slides, 37, mounted in slideways, 38, extending transversely through the bed, the outer ends 15 of which slides are adapted to abut against the respective claw-members, 30.

The inner ends of these slides, 37, are engaged by a cam-plate, 39, slidably mounted in a longitudinal slideway, 40, formed in the 20 bed, and adapted to be operated by means of a handle, 41.

Forward movement of the cam-plate, 39, serves to wedge apart the slide-plates, 37, and thus to force apart the claw-members, 25 30, so that their claws, 35, shall not overhang said space on the bed.

Rearward movement of the cam-plate, 39, releases the claw-members, 30, to the action 30 of their respective springs, 36, which serve to restore said members to a position such that their claws, 35, overhang said space.

The space on the bed thus bounded by the claw-members, 28, 29 and 30, is adapted to receive the pair of tube-connected brush-35 plates suitably supported; and in Fig. 5, I have shown said tube-connected plates suitably supported and mounted upon the bed within said space.

For convenience in comparison, I have 40 designated the two tube-connected plates and the parts directly associated therewith as shown in said prior patent with the same reference characters used to designate the respective parts in said patent.

Thus, 1, is the rubber-pad clamped or embraced between the lower clamp-plate, 3, and the upper clamp-plate, 4, the lower clamp-plate, 3, resting upon a suitable support or base, 7; and 5 is the tube-plate, carrying the 50 tubes, 6, which are shown forced down through the openings in the upper clamp-plate, 4, rubber-pad, 1, and lower clamp-plate, 3.

Bristles, 42, are shown inserted within the 55 respective tubes.

In accordance with my invention, I form the upper clamp-plates, 4, with edge-portions, 4^a, which project outwardly beyond the edges of the tube-plate, 5, at points 60 where the upper clamp-plate, 4, is to be engaged by the claws on the claw-members, 28, 29 and 30.

In mounting the tube-connected plates and their support upon the bed, 21, for the 65 stripping operation, the front claw-mem-

bers, 28, are swung forward by hand to the position shown in Fig. 6 in which they are substantially in the plane of the bed, 21, and the claw-members, 30, are forced apart to the position indicated by dotted lines in 70 Fig. 1, by drawing forward the cam-slide, 39, by means of its handle, 41, to the position indicated by dotted lines in Fig. 4.

The tube-connected plates and their support, 7, are then placed upon the bed, 75 21, with the claws, 31, overhanging the projecting edge-portions, 4^a, of the upper clamp-plate, 4, whereby said upper clamp-plate, 4, the rubber-pad, the lower clamp-plate, 3, and the support, 7, are all held 80 against upward movement.

I have shown a pair of guide-plates, 43, at opposite sides of the space occupied by the support, 7, to facilitate the placing of 85 the support, 7, upon the bed, 21.

Fixed upon the lower end of the plunger, 26, is a spider having members, 44, upon which are pivotally mounted a pair of front claw-members, 45, terminating at their lower ends in claws, 46.

The spider also has members, 47, upon which are pivotally mounted a pair of rear claw-members, 48, terminating at their lower ends in claws, 49.

The spider also has members, 50, on opposite sides upon which are pivotally mounted side claw-members, 31, terminating at their lower ends in claws, 52.

A yoke-shaped handle-lever, 53, is pivotally mounted at 54, upon the overhanging 100 arm, 22, inclosing the head, 23, pivotally depending from the branches of which lever are links, 55, one at each side of the head, 23.

The link, 55, at each side of the head, 23, 105 is connected by a link, 56, with the neighboring side claw-member, 51, whereby as the links, 55, are raised by upward movement of the handle lever, 53, the side claw-members, 51, will be moved in a direction to move 110 their claw-ends, 52, outwardly, that is, away from each other, while downward movement of the handle-lever, 53, will cause said claw-ends to be moved toward each other.

A rod, 57, extends through the upper ends 115 of the front claw-members, 45, the opposite ends of the rod being connected by links, 58, with the respective links, 55, and the rear claw-members, 48, are in like manner connected by a rod, 59, the ends of which are 120 connected by links, 60, with the respective links, 55, whereby upward movement of the handle-lever, 53, actuates the front and rear claw-members to move their claw-ends away from each other, while downward movement 125 of the handle-lever causes said claw-ends to be moved toward each other.

I also mount upon the bottom of the spider a presser-plate 61, yieldingly forced downward by coil springs, 62, into engage- 130

ment with the tube-plate, 5, when the tube-plate is in position to be engaged by the claws, 46, 49 and 52.

The operation of the machine is as follows:

The tube-connected plates having been placed upon the bed in the position shown in Fig. 5, in the manner above described, the cam-plate, 39, is forced rearwardly by 10 means of the handle, 41, releasing the slides, 37, to the action of the coil-springs, 36, which force toward each other the claw-members, 30, to cause their claws, 35, to overhang the edge-portions, 4^a, of the upper clamp-15 plate, 4; and in the front claw-members, 28, are swung upward and rearward to cause their claws, 33, to overhang the front edge-portions, 4^a, of said plate, while the rear edge-portions, 4^a, thereof are held beneath 20 the claws, 31, of the rear claw-members, 29.

The upper clamp-plate, 4, is formed with notches, 4^b, in line with the respective claw-members, 45, 48 and 51, carried by the plunger, 26.

After the tube-connected plates have been placed and secured upon the bed as above described the plunger, 26, is lowered by raising the handle, 24, while the claw-ends of the claw-members 45, 48 and 50, 30 are spread apart by upward movement of the hand-lever, 53.

When the plunger, 26, has been sufficiently lowered to somewhat compress the springs, 62, through engagement of the presser-plate, 35 61, with the tube-plate, 5, the handle-lever, 53, is forced downward thereby forcing inward the claw-ends of the claw-members, 45-48 and 50, causing said members to enter the respective notches, 4^b, in the upper 40 clamp-plate, 4, and their claws to underlyingly engage the tube-plate, 5.

The handle, 24, is then forced downward to raise the plunger, 26, which carries with it the tube-plate, 5, engaged by the claws on 45 the claw-members, 45, 48 and 50, while the upper clamp-plate, rubber-pad, lower clamp-plate and support, 7, are all held down upon the bed by the engagement of 50 the claws on the claw-members, 28, 29 and 30, with the upper side of the upper clamp-plate, 4.

The tube-plate, 5, is held by the spring-actuated presser-plate, 61, closely against the claws on the claw-members, 45, 48 and 50, during the operation and thereafter until the tube-plate is released by upward movement of the handle-lever, 53, whereby said claw-ends are again separated.

What I claim as new and desire to secure 60 by Letters Patent is—

1. In a machine of the class described and in combination, a bed; a member movable toward and from the bed; means for moving said member toward and from the 65 bed; claw-members mounted upon the

bed; and claw-members carried by said movable member with their claws in opposed relation to the claws on the bed-claw-members.

2. In a machine of the class described and in combination, a bed; a member movable toward and from the bed; means for moving said member toward and from the bed; claw-members mounted upon the bed at opposite sides and opposite ends of a space adapted to receive a pair of suitably supported tube-connected brush-plates; claw-members mounted upon said movable member with the claws in opposed relation to and out of alinement with the respective claws on the bed-claw-members. 70 75

3. In a machine of the class described and in combination, a bed; a member movable toward and from the bed; means for moving said member toward and from the bed; claw-members mounted upon said movable member; and claw-members mounted upon the bed movable to and from a position overhanging a space on the bed under said movable member, the claws on said last-mentioned claw-members being in opposed relation to the claws on the first-mentioned claw-members. 80 85

4. In a machine of the class described and in combination, a bed; a member movable toward and from the bed; means for moving said member toward and from the bed; claw-members mounted upon the bed at opposite sides and opposite ends of a space adapted to receive a pair of suitably supported tube-connected brush-plates under said movable member; claw-members mounted upon said movable member in opposed relation to and out of alinement with the respective claws on the bed-claw-members; and means for moving said last-mentioned claw-members into and out of position to underlyingly engage the uppermost 90 95 100 of said tube-connected brush-plates. 105

5. In a machine of the class described and in combination, a bed; a member movable toward and from the bed; means for moving said member toward and from the bed; claw-members mounted upon the bed movable to and from a position for their claws to overhang a space on the bed under said movable member adapted to receive a pair of suitably supported tube-connected brush-plates; claw-members mounted upon said movable member with the claws in opposed relation to and out of alinement with the respective claws on the bed-claw-members; and means for moving said last-mentioned claw-members to and from a position in which their claws are adapted to engage the underside of the uppermost of said tube- 110 115 120 125 connected plates.

6. In a machine of the class described and in combination, a bed; a member movable toward and from the bed; means for moving said member toward and from the 130

bed; claw-members mounted upon the bed at opposite sides and opposite ends of a space adapted to receive a suitably supported pair of tube-connected brush-plates; 5 claw-members mounted upon said movable member with the claws in opposed relation to the respective claws on the bed-claw-members; and a plate yieldingly mounted on

the under side of said movable member in position to engage one of said tube-connected plates and yieldingly hold the same against the claws of the claw-members mounted on said movable member. 10

In testimony whereof, I have hereunto set my hand this 21st day of May, 1920.

WM. T. SHERMAN.
